METHOD OF ERECTING CONCRETE
STRUCTURES

Paul Plückebaum, Am Sandacker 22,
Düsseldorf-Hamm, Germany

Filed Sept. 14, 1962, Ser. No. 223,799

Claims priority, application Germany, Apr. 2, 1959,
P 22,517; May 11, 1962, P 29,379
2 Claims. (Cl. 264—34)

My present invention relates to the construction of multistory buildings by a method wherein the concrete framework (ceiling and supporting columns) of an upper story is completed substantially at ground level and is thereafter elevated so that the framework of the next-lower story may be similarly completed; this method has been disclosed in my copending application Ser. No. 17,042, filed March 23, 1960, and now abandoned, of which the present application is a continuation-in-part.

The construction method outlined above offers the advantages that the work of erecting the framework is carried out substantially exclusively at or near grade level, i.e., on, slightly above or below the ground, so as to minimize the danger of accidents; that the finishing of each story (e.g., erection of outer walls and partitions, installation of plumbing and construction of stairways) may proceed, again at relatively low elevation, immediately upon the hardening of its concrete framework and concurrently with the casting of the ceilings and columns of a lower story, thereby affording a considerable saving of time; and that most of the work can be done in the shelter of a roof section initially provided over the rising structure.

A general object of this invention is to provide an improved system for erecting multistory buildings by this method and, in particular, insuring a firm and direct concrete-to-concrete bonding between the horizontal slabs and the vertical columns of successive stories whereby the entire building, or at least that part of it which is to be erected by this method, will be joined into a unitary, 40 monolithic concrete skeleton.

A more particular object of this invention is to provide means for protecting the most recently formed part of the structure, i.e., the momentarily lowermost story, against lateral stresses such as may arise from strong winds which could, if unchecked, impair the stability of the building.

A further object of my present invention is to provide simple and effective means for gradually and uniformly elevating the several columns of each newly completed story framework preparatorily to the erection of the next-lower story.

In accordance with a feature of this invention I provide, at the location of each concrete column to be erected, a set of upright posts which are peripherally spaced about the column site and serve as temporary supports for the column and its falsework. Advantageously, in the case of columns with polygonal cross-section, these posts are disposed adjacent respective corners of the polygon and are interconnected by horizontal braces adapted to accommodate wedge pieces loosely inserted between these braces and an adjacent form board whereby the latter can be elevated together with its column but is frictionally prevented from sliding back toward the ground. The posts, rising from a foundation which may be on the ground but can also be disposed within a pit subsequently accommodating a basement floor, are preferably made of structural steel and may be composed of separable longitudinal sections to facilitate their removal upon completion of the structure. The falsework for the horizontal slabs forming the ceilings and floors of the structure can also be conveniently supported on these posts and will usually be so shaped as to define a set of horizontal

2

reinforcing ribs which radiate outwardly from the sides of each column along the associated slab.

When the columns and slabs have hardened sufficiently to sustain the weight of the overlying structure, they are elevated by the height of one story, e.g., with the aid of hydraulically controlled jacks, whereupon the concrete framework may be temporarily but positively anchored to the posts by suitable supporting bars which are secured to the posts, e.g., by being thrust through suitable cutouts therein, so as to be contacted by the undersides of the reinforcing ribs of the slabs; the aforementioned braces together with their wedge pieces may then be removed to the extent necessary to enable the subsequent rise of the next story framework to its elevated position.

15 The invention will be described hereinafter in greater detail with reference to the accompanying drawing in which:

FIGS. 1-4 schematically illustrate the erection of a multistory building by the aforescribed method, these figures being generally similar to the FIGS. 1-4 of my application Ser. No. 17,042;

FIG. 5 is an enlarged elevational view, partly in section, of an assembly for erecting such multistory building, shown in a position preparatory to the casting of a lower-story framework;

25 FIG. 6 is a view generally similar to FIG. 5, illustrating the cast framework in a partly elevated position;

FIGS. 7 and 8 are cross-sectional views taken on the lines VII—VII and VIII—VIII, respectively, of FIG. 5;

FIG. 9 is a sectional view taken on line IX—IX of FIG. 5, showing the elevating mechanism;

FIG. 10 is an enlarged fragmentary view of the same mechanism;

FIG. 11 is a cross-sectional view taken on line XI—XI of FIG. 10;

FIG. 12 is a sectional elevational view of the base of a column in a slightly modified system; and

FIG. 13 is a fragmentary sectional elevational view illustrating a further step in the erection of a building with the modification shown in FIG. 12.

Reference will first be made to FIGS. 1-4 for a general description of the herein contemplated method of erecting a multistory building. As shown in FIG. 1, a pit is dug in the ground G to accommodate equipment, schematically represented by a set of hydraulically operated jacks J, for the progressive elevation of a building structure to be erected overhead. As the first part of the structure, a roof R is disposed above the pit on the jacks J and is subsequently elevated (FIG. 2) to make room for the erection of the framework for the uppermost story here designated III. Next, as shown in FIG. 3, story III with the overlying roof R is similarly raised preparatorily to the construction of the next-lower story II. The bottom story I is constructed, as illustrated in FIG. 4, upon the subsequent elevation of the previously completed part II, III, R of the building skeleton whereupon, as a final step, a basement floor B may be installed within the pit. Part of this basement can, of course, also have been completed at an earlier stage.

60 Details of the equipment used to erect and elevate successive story frameworks have been illustrated in FIGS. 5-11. FIG. 5 shows a foundation 20 which may be sunk into a basement or ground-level floor, supporting a set of steel beams 21 arrayed about the location of a concrete

65 column C₂. This column, along with similar columns (not shown) and an overlying horizontal slab S₂ spanning these columns, forms part of a framework of an intermediate story of a building in the process of erection; the corresponding column of the next-higher story is shown at C₁. Slab S₂ is formed on its underside with a network of reinforcing ribs or beams B₂ which con-

verge at the square column C_2 and terminate at the four sides thereof.

A vertically movable lead screw 22, forming the ram of a jack shown at J in FIGS. 1-4, is centrally disposed within the foundation 20 between the uprights 21 in alignment with the columns C_1 , C_2 thereabove. The false-work necessary for the erection of each story framework is generally shown at 23 and includes vertical boards 23a, defining a column shaft, as well as horizontal boards 23b which conform to the horizontal reinforcing ribs of the slab to be poured. Boards 23b and other slab-supporting parts of the falsework 23 rest on supports 24 which are removably secured to the uprights 21 and are braced by auxiliary posts 25.

A set of horizontal braces 26 (FIGS. 5-8) are demountably secured to the uprights 21 at various levels, with the aid of bolts 27 passing through threaded holes 28, at each of the four sides of the array at a small distance from the corresponding form board 23a. The braces 26 have beveled surfaces 26a which adjoin the form boards and diverge upwardly therefrom so as to accommodate a wedge piece 29 designed to back-stop the mold and its column against accidental descent in their elevated position (see FIG. 6). The wedge pieces 29 yield readily in an upward direction so as not to interfere with the elevation of the mold by its ram 22. This ram acts upon the column through a distributor plate 30 which, in addition to supporting the boards 23a and the column, prevents the concrete from flowing into the cavity 31 of the foundation 20 when the column is poured. Other, stationary plates 32 rest on the foundation to support the uprights 21.

As best seen in FIG. 6, each upright 21 is composed of a series of longitudinally adjoining sections 21a which are held together by bolts 33 and, as shown, may be box-type steel channels of square cross-section. At second-floor level these uprights are shown enveloped by sheaths 34, e.g., of anti-bonding tape, in order to facilitate the raising of the slab poured therearound. They furthermore are formed, just below second-floor level, with cutouts 35 designed to receive positively acting backstop means in the form of bars or shims 36 serving to support whichever slab has reached the position of slab S_2 in FIG. 5.

Reference will now be made to FIGS. 9-11 which illustrate a suitable mechanism for elevating the ram 22 with its overlying distributor plate 30. Ram 22, held against rotation by stationary key 39d in engagement with its vertical groove 22a, is surrounded by two mating nuts 37, 38 which are rotatably journaled in bearing shells 39a, 39b within a housing 39 and are shown interconnected for joint rotation by means of longitudinal bolts 40. Nut 37 is rigid with an upper gear 41 which meshes with a pinion 42 loosely journaled on a shaft 43; a second pinion 44, also loosely journaled on shaft 43, drives the nut 38 via a lower gear 45, rigid with that nut, through the intermediary of a direction-reversing pinion 46. Shaft 43 entrains the pinions 42 and 44 through respective unidirectional clutches 47 and 48, e.g., ratchet couplings, which are so arranged that one of the pinions (i.e., 44) will follow only clockwise rotation whereas the other pinion will follow only counterclockwise rotation as indicated by the arrows in FIGS. 10 and 11. Shaft 43 is rigid with an arm 49 articulated, by way of a pitman 50, to the rod 51 of a piston 52 inside a hydraulic cylinder 53. Nuts 37 and 38 will thus execute a clockwise motion, adapted to elevate the threaded ram 22, upon each stroke of piston 52 in either direction. Pipes 54 and 55 extend from cylinder 53 to a source of hydraulic fluid, not shown, for alternately admitting such fluid to opposite sides of piston 52 under the control of a suitable valve mechanism of conventional construction. The lower end of shaft 43 is journaled in an extension 39c of housing 39 which also encloses the pinion 44 with its clutch 48.

The nuts 37, 38 may be selectively decoupled from their hydraulic piston 52, e.g., by inactivation of their ratchet clutches 47 and 48, in order to facilitate the descent of the ram 22 after it has been raised to its highest position. The raising of the ram proceeds at a relatively slow rate, e.g., of less than 1 mm. per piston stroke, and all pistons of the system are concurrently actuated at the same rate by their common control unit.

In the ensuing description of the operation of my improved system it will be assumed that, as illustrated in FIG. 5, one or more upper stories have already been completed and are held above ground level by bars 36 engaging the underside of reinforcing ribs B_2 . At this stage the base of column C_2 rises above the level of the horizontal form board 23b by at most the thickness of a slab S_1 with its ribs B_1 (FIG. 6) to be cast thereon. The falsework 23 has been positioned for the casting of such slab and its column C_1 (FIG. 6). The usual reinforcing elements E' (for the slab) and E'' (for the column) have been laid in, it being noted that the column reinforcements E'' extend into the cavity 31 through slots 30a left for this purpose in distributor plate 30. Wedges 29 are in place alongside the boards 23a to stiffen them against lateral displacement and back-sliding, such wedges being also inserted between column C_2 and braces 26 at the level of the second story where they bear directly upon the hardened column.

With the pouring of the concrete to form a lower-story framework immediately above the foundation 20, the structure has been monolithically extended downwardly as the base of column C_2 merges with and is bonded to slab S_1 . After sufficient hardening, the entire building skeleton together with its falsework 23 is elevated by a concurrent raising of all its columns, in the aforescribed manner, as has been illustrated in FIG. 6. It will be apparent that, in view of the presence of bridge pieces between the slab S_1 and the column C_1 , such raising requires the prior removal of the second-story braces 26, e.g. successively from bottom to top in order to maintain the vertical guidance of column C_1 as long as possible. Naturally, the shims 36 will also have to be withdrawn from their cutouts 35 before the slab S_1 can be lifted into the erstwhile position of slab S_2 .

Although the dismounting and re-establishment of the form may be carried out in various ways and at different stages of the operation, it may be convenient to let at least the boards 23a and 23b (which may be interconnected) travel with the newly cast column along all or part of its one-story rise and to restore them to their original position upon removal of the remaining wedges 29. Shims 36 are reinserted to support the ribs B_1 of slab S_1 before the ram 22 together with plate 30 is returned to its withdrawn position within foundation 20; the second-story braces are also remounted at that stage, though of course the lower ones of these braces could also have been installed earlier to help support the rising column C_1 . It will be apparent that the vertical reinforcements E'' , which have cleared the slots 30a of plate 30, now remain suspended below the level of boards 23b so as to become anchored to the next column and slab to be poured.

When the structure has been fully erected, the framework of the last story is not elevated but allowed to remain at ground level where it has been cast. Subsequently, the uprights 21 and the auxiliary supports 24, 25 are disassembled and removed whereupon the gaps left by the uprights in the slabs of the lowermost story or stories can be filled; corresponding gaps in the higher slabs could, of course, have been filled at an earlier stage, i.e. as soon as these slabs rose above the tops of the uprights. The elevating mechanism is extracted from the foundation 20 which, if desired, may be further excavated to accommodate a basement.

In FIGS. 12 and 13 I have shown that it is possible to obtain a monolithic structure by the present method even

if an upper column C_1' is elevated only so far that its base lies at or below the lower surface of the ribs B_2' of a lower-story slab S_2' poured thereafter. In this case I may insert a removable core 56 into the lower end of the column so as to leave therein a sloping channel 56a through which concrete may subsequently be poured for the casting of the next-lower column C_2' as an integral extension of column C_1' .

It will be apparent that jacks and other means serving to elevate a cast and hardened framework may be brought to bear at other or supplemental locations, e.g. upon the undersides of the reinforcing ribs or beams B_1 , B_2 etc., and that the mechanism illustrated in FIGS. 10 and 11 (though of advantageous construction) is representative of various alternate lifting devices. These and further modifications, not specifically described, will be readily apparent to persons skilled in the art and are intended to be encompassed in the spirit and scope of my invention as defined in the appended claims.

I claim:

1. A method of erecting a concrete skeleton for a multistory building having a plurality of superposed one-story frameworks of slabs and columns, comprising the steps of:

- (a) excavating a recess in the ground with a depth of at least one story and forming in the resulting excavation a foundation for said skeleton;
- (b) erecting on said foundation an array of fixedly positioned upstanding support members, having a height of at least two stories, about the site of each column of a framework to be cast;
- (c) temporarily mounting upon said support members a concrete-molding formwork including form boards for each column disposed within said array;
- (d) inserting between said form boards a set of elongated generally vertical reinforcing members for each column, at least some of said reinforcing members having ends projecting downwardly into said excavation;
- (e) monolithically pouring each column between said form boards and an overlying slab spanning all the

10

15

20

25

30

35

40

columns so poured, thereby forming a framework for an uppermost story of the building;

- (f) allowing said framework to harden into a structure sufficiently rigid to be elevated above said foundation;
- (g) elevating said structure by lifting each column thereof to a second-story level with the aid of respective jacks disposed in said recess whereby said projecting ends extend downwardly below said level;
- (h) temporarily retaining said structure on said second-story level by bracing it against said support members while withdrawing the jacks into said recess preparatorily to the pouring of a framework for the next-lower story of the building;
- (i) and proceeding in like manner in the formation of a similar framework for each subsequent story, with the columns of all frameworks mutually aligned and with insertion of reinforcing members between the form boards for the lower columns in overlapping relationship with the ends of the reinforcing members from the upper columns.

2. The method defined to claim 1 wherein said support members are removed upon completion of the last framework.
